UNITED STATES PATENT OFFICE.

ARTHUR THOMAS TIMEWELL, OF CHICAGO, ILLINOIS, ASSIGNOR TO
ALBERT DICKINSON, OF CHICAGO, ILLINOIS.

FILLED-SACK-SEWING MACHINE.

SPECIFICATION forming part of Letters Patent No. 684,959, dated October 22, 1901.

Application filed October 3, 1898. Serial No. 692,475. (No model.)

To all whom it may concern:

Be it known that I, ARTHUR THOMAS TIMEWELL, a citizen of the United States, residing in Chicago, in the county of Cook and State of Illinois, have invented a new and useful Improvement in Filled-Sack-Sewing Machines, of which the following is a specification.

My invention relates to filled-sack-sewing machines, and more particularly to improvements upon the filled-sack-sewing machine heretofore patented to me in Letters Patent of the United States No. 607,809, dated July 19, 1898. In the machine of my said former patent the mouth edges of the filled sacks are conveyed past the sewing mechanism by a pair of endless flexible sack-holding clamps or chains, the chains being driven continuously and conveying the sack by a continuous movement past the sewing mechanism.

The object of my present improvement is to perfect the operation of the machine of my said former patent; and the present improvement consists in providing said machine with means for facilitating the feeding or entering of the mouth edges of the sack into the bight of the continuous flexible sack-holding clamps or chains, said means consisting, preferably, in a pair of toothed or roughened sack-feed wheels mounted somewhat in advance of the sprocket-wheels around which the conveyer-chains pass, so that the sack-feed wheels will tend to feed or force the fabric of the sack into the bight of the sack-holder chains.

It also consists, in connection with the sack-holder chains and said feed-wheels, in mechanism for driving said feed-wheels at a faster speed than the sack-holder chains, preferably about double the speed of the sack-holder chains, so that the sack-feed wheels will also serve to gather the mouth edges of the sack preparatory to their being fed into the sack-holder chains and sewed, thus materially shortening the necessary length of the seam and greatly strengthening the mouth of the sewed sack at the seam and also improving the appearance of the sewed filled sack.

My invention further consists in providing the endless flexible sack-holder clamps or chains with a rapidly intermittent driving mechanism, so that said sack-holding chains may be stationary or substantially stationary

at the intervals when the needle is in the sack, the forward movement of the sack taking place or chiefly taking place under the action of the chains when the needle is out of the fabric. As in my filled-sack-sewing machine the needle ordinarily makes about fifteen hundred stitches per minute, it will be understood that this gives a corresponding number of starts and stops to the sack-holding chains per minute. By this means the operation of the machine is materially improved, the needle is freed from all lateral strain, and the durability of the sewing mechanism increased.

Any suitable mechanism for driving or propelling the sack-holding chains forward by a rapid succession of impulses may be employed in combination with the other parts in practicing this feature of the invention; but I prefer to employ for this purpose a rapidly revolving two-toothed gear engaging a toothed wheel, through which motion is communicated to the sack-holding chains.

In the accompanying drawings, forming a part of this specification, Figure 1 is a plan view of a machine embodying my invention. Fig. 2 is a detail front elevation. Fig. 3 is a detail side elevation of the preferred form of mechanism for imparting to the sack-holding chains the necessary rapid intermittent forward movement, and Figs. 4 and 5 are side elevations showing the sack before being sewed and after.

In the drawings, A represents the frame or bed-plate of the machine, the same being provided with a longitudinal slot a for the mouth edges of the sacks to project through as they are being conveyed past the sewing mechanism. The slot a is spanned by bridges A' A'. The frame or bed-plate A is also provided with guides C C to guide the endless flexible sack-holder clamps D D, the same consisting, preferably, of two endless chains traveling on suitable sprocket-wheels d d'.

F F' are the sack-feed wheels, the bight of the wheels F F' being in advance of the bight of the chains D D, so that the feed-wheels F F' will serve to force the edges of the sack-mouth into the bight of the sack-holder chains or flexible clamps D D, as will be readily understood from Fig. 1 of the drawings. The feed-wheel F' is mounted on a pivoted or

swinging arm F^2 and is pressed against its fellow with the requisite tension or pressure by a spring F^3 . The feed-wheel F' is an idler; but the feed-wheel F is driven and preferably at a greater surface speed than that of the sack-holding chains or clamps $D D$, so that the feed-wheels $F F'$ operate also as a gathering mechanism to gather the mouth edges of the sack, as illustrated in Fig. 5, and thus shorten the necessary length of the seam. The feed-wheel F is secured rigidly to a shaft f , which is provided with a bevel-gear f' , meshing with bevel-gear f^2 on shaft f^3 , through which motion is communicated to the feed-wheels $F F'$. One of the loose or idler sprocket-wheels d' for one of the endless flexible clamps or chains D is journaled upon the shaft f of the feed-wheel F and is preferably made of approximately the same diameter as the feed-wheel F , though somewhat smaller, in order that the bight of the feed-wheels $F F'$ upon the mouth of the sack may be only slightly in advance of the bight of the sack-holder chains $D D$ upon the sack.

25 The sewing mechanism B may be of any suitable construction known to those skilled in the art and needs no special description. I prefer to employ, however, the construction of sewing mechanism illustrated and described 30 in my said former patent.

35 G is the driving-pulley, and G' the driving-shaft, from which motion is communicated to the different parts of the machine. Motion is communicated to the sewing mechanism B from the driving-shaft G' through the bevel-gears $g g'$. The driving-shaft G is furnished with a two-toothed gear g^2 , which meshes with a long-toothed gear g^3 , and thus communicates a rapidly intermittent rotation to said 40 long-toothed gear, as will be readily understood from Fig. 3 of the drawings. The long-toothed gear g^3 is fixed to a shaft g^4 , which is provided with a bevel-gear g^5 , through which motion is communicated to the bevel-gear g^6 45 on the shaft g^7 , by which the sack-holding chains $D D$ are driven through the bevel-gears $g^8 g^9$, meshing with the bevel-gears $g^9 g^9$ on the shafts g^{10} , which carry the driven sprocket-wheels $d d$ for each chain D . The 50 shaft f^3 is provided with a bevel-gear f^4 , that meshes with the bevel-gear g^5 , so that the shaft f^3 and the feed-wheels $F F'$ thus have a corresponding intermittent movement to the chains $D D$. The shafts f^3 and g^7 run 55 at the same speed, and the feed-wheel F is caused to travel at the required greater surface speed than the chains $D D$ by reason of the gear f^2 on said shaft f^3 being of larger size than the gears g^8 on the shaft g^7 which 60 communicate motion to the driven sprocket-wheels $d d$ of the chains $D D$, and the gears

g^9 on the shafts of said driven sprocket-wheels g^8 are also of larger size than the gear f' on the shaft f of the driven feed-wheel F . By varying the relative sizes of these gears 65 any required or desired difference of speed may be given to the feed-wheels $F F'$ in respect to that of the sack-holder chains $D D$. I claim—

1. In a filled-sack-sewing machine, the combination with a sewing mechanism, of flexible endless traveling sack-holder clamps and a pair of sack-feed wheels in advance thereof to force or feed the edges of the sack-mouth into the bight of the flexible sack-holder 70 clamps, substantially as specified.

2. In a filled-sack-sewing machine, the combination with a sewing mechanism, of flexible endless traveling sack-holder clamps, a pair of sack-feed wheels in advance thereof to force 80 or feed the edges of the sack-mouth into the bight of the flexible sack-holder clamps, and mechanism for driving said feed-wheels at a faster surface speed than the sack-holder 85 clamps to produce gathers in the edges of the sack-mouth before it enters the clamps, substantially as specified.

3. In a filled-sack-sewing machine, the combination of a sewing mechanism with a pair of endless flexible traveling holder-clamps, a 90 pair of guides therefor to cause them to clamp and hold the sack-mouth between them, and mechanism for imparting a rapidly intermittent forward movement to said endless flexible sack-holder clamps, the forward step-by-step movement of said sack-holder clamps taking place at the intervals when the needle of the sewing mechanism is withdrawn from the sack, substantially as specified.

4. In a filled-sack-sewing machine, the combination with a sewing mechanism, of an endless flexible traveling sack-holder clamp, and means for producing gathers in the edges of the sack-mouth, said means comprising a pair of wheels rotating at a faster speed than 100 the sack-holder clamp travels, substantially as specified.

5. The combination in a filled-sack-sewing machine, with a sewing mechanism, of a pair of endless, flexible traveling sack-holder 110 clamps, having each a recurrent travel in an endless path, a pair of guides therefor to cause them to clamp and hold the sack-mouth between them, and mechanism comprising a two-toothed gear and a long-toothed gear for 115 imparting a rapidly intermittent forward movement to said sack-holder clamps, substantially as specified.

ARTHUR THOMAS TIMEWELL.
